GAS TUBE RADIO-FREQUENCY SWITCH

Warren H. Flarity, Washington, D. C.

Application January 7, 1949, Serial No. 69,764

6 Claims. (Cl. 313—193)

(Granted under the act of March 3, 1883, as
amended April 30, 1928; 370 O. G. 757)

1

This invention relates to switch devices and more particular to three-element gaseous switch tubes.

In the past, controlled high-speed switching of high-power radio-frequency energy has been impossible because of the lack of a switch tube capable of being exposed to the high-power energy to be switched without being rendered conductive thereby. It is therefore the general object of this invention to provide a gaseous switch tube which is solely responsive to a signal applied to its control element.

The present invention, therefore, is not to be confused with transmit-receive tubes commonly used in radar systems to permit use of one antenna for both transmitting and receiving. Transmit-receive tubes are made conductive by the high-power transmitter pulse with the result that the pulse is directed to the antenna. By contrast, the tube of the present invention is responsive to a control signal and is not affected by the high-power energy to be switched.

While the switch tube of the present invention is suited for application in a great many ways, as will be apparent to those skilled in the art, the tube is especially useful as a part of a system for high-speed switching of high-power radio-frequency energy. Such a system is described in a copending application, Serial No. 69,765, filed January 7, 1949. With this system it is possible to switch a source of high-power radio-frequency energy from one load to another in a fraction of a microsecond. The switching is performed in response to a signal applied to the switch tubes of the system.

Many other objects and advantages of the switch tube will be apparent to those skilled in the art from a perusal of the following description taken in conjunction with the appended drawings of one embodiment of the invention. In the drawings:

Fig. 1 is a sectional view taken longitudinally through a tube constructed in accordance with the teaching of this invention.

Fig. 2 is a transverse sectional view of the same taken on the line 2—2 of Fig. 1.

Fig. 3 is another transverse sectional view of the same taken on the line 3—3 of Fig. 1.

Referring now in greater detail to the drawings, a metallic disk 10 is made of an alloy such as Kovar which is adapted for forming a glass-to-metal seal. The disk 10, which of course need not be circular in outline, is provided with a centrally disposed aperture 11. A cylindrical grid support 12 of nickel or other suitable material is

2

mounted on the surface 13 of disk 10 in coaxial relationship with the aperture 11. The extended end of the cylindrical grid support 12 is covered by a wire mesh grid 14. A nickel grid having 40 lines per inch in each direction was found to give good results. The disk 10, cylindrical grid support 12 and grid mesh 14 may together be considered as a control element structure.

A vitreous or metallic cylindrical shell 17 has an annular edge portion 18 sealed to the surface 13 of disk 10, the shell 17 being disposed in substantially a coaxial relationship with the aperture 11 in the disk 10. The shell 17 includes a support portion 19 having cathode posts 20 and 21 fused therein. An electron emissive cathode 22 is connected by wire 23 to post 20, and has an internal heater coil connected by wire 24 to post 20 and by wire 25 to post 21. Flexible leads 26 and 27 connected to posts 20 and 21 respectively are disposed externally of the shell 17 and are adapted for connection to a source of heater voltage. A control voltage for rendering the tube conductive may be applied across the disk 10 and lead 26. The voltage so applied is effectively across the grid 14 and the cathode 22.

A cylindrical anode 30 of Kovar has one end 31 disposed coaxially in the aperture 11 and in the cylindrical grid support 12. Good results have been obtained with a grid-to-anode spacing of about $\frac{1}{2}$ of an inch. The other end 32 of the anode 30 is intended for connection to an inner conductor, for example, of a coaxial line. The anode 30 is maintained in position by means of a vitreous seal 33 fused to the surface 34 of the disk 10 and around an intermediate portion of the anode 30.

It is apparent from the foregoing that the shell 17, the seal 33 and the disk 10 cooperate to form an envelope the interior of which is divided into two chambers by the disk 10. The aperture 11 in the disk 10 provides communication between the two chambers. The interior of the envelope is provided with an inert gas such as argon at a pressure in the order of 150 microns, for example. The gas pressure used should be as low as possible, but not so low as to appreciably decrease the life of the tube. The tube should have a gas pressure such as to be operated up on the low-pressure leg of the Paschen law curve of breakdown voltage (between the anode and grid) versus gas pressure.

In use, the switch tube is secured to a conduit or chamber for radio-frequency energy. The conduit or chamber may be a coaxial line, a wave

guide, a resonant cavity, or the like. The tube may be arranged with the disk 10 on the exterior of the conduit or chamber and with the anode 30 and seal 33 extending through an aperture in the conduit or chamber to the interior thereof. Many possible methods of utilizing the switch tube, as for example in conjunction with a quarter-wave stub, will suggest themselves to those skilled in the art. In use, the anode 30 and vitreous seal 33 are exposed to the radio-frequency energy to be switched, but the energy cannot ionize the gas in the envelope by reason of the attenuation through the vitreous seal and the structural relationship of the parts of the tube.

A source of heater voltage is applied to the leads 26 and 27. The switch tube is rendered conductive, with the result that the anode 30 is placed in electrical contact with the disk 10, when a control voltage is applied across the disk 10 (grid 14) and lead 26 (cathode 22). The control voltage may be in the form of a firing pulse. The tube may be rendered conductive in a fraction of a microsecond after application of a firing signal. When used in conjunction with an appropriate system of conduits or chambers, a high-power pulse of radio-frequency energy having a duration of a few or several microseconds may be split into two parts and each applied to a different load.

While one embodiment of the invention has been shown and described in some detail, it is to be understood that this has been done by way of illustration and not by way of limitation. It is accordingly desired that the appended claims be given a broad interpretation commensurate with the spirit and scope of the invention.

The invention described herein may be manufactured and used by or for the Government of the United States of America for governmental purposes without the payment of any royalties thereon or therefor.

What is claimed is:

1. A gaseous switch tube comprising an apertured metallic disk, a vitreous envelope sealed to the flat surfaces of the disk and forming a chamber on each side of the disk, the aperture in the disk providing communication between the chambers, a cylindrical grid support extending from the disk coaxially with the aperture into one of said chambers, a grid across the extended end of the cylindrical grid support, a cathode in the same chamber, and an anode in the other chamber having a portion disposed coaxially in the aperture in the disk.

2. A switch tube comprising an apertured metallic disk, a cylindrical grid support extending from one side of the disk coaxially with the aperture therein, a grid across the extended end of the grid support, an enclosure-forming shell sealed to the same side of the disk and a cathode in the enclosure, an anode coaxially disposed in the disk aperture and grid support and extending

from the other side of the disk, and a vitreous seal between said other side of the disk and an intermediate portion of the anode.

3. A gaseous switch tube comprising an apertured metallic disc, a gas filled envelope made of a non-conducting material sealed to the flat surfaces of the disc providing a chamber on each side thereof, the aperture in the disc providing communication between the chambers, control grid structure electrically connected to said disc and covering said aperture, a cathode in one of said chambers, and an anode in the other chamber having a portion disposed coaxially in the aperture in the disc.

15 4. A gaseous switch tube comprising an apertured metallic disc, a gas filled envelope made of a non-conducting material sealed to the flat surfaces of the disc and forming a chamber on each side thereof, the aperture in the disc providing communication between the chambers, control grid structure electrically connected to said disc and covering said aperture, a cathode in one of said chambers, and an anode in the other chamber having a portion disposed in the aperture in the disc.

20 5. A gaseous switch tube comprising an envelope member forming a first chamber containing gas at low pressure, an aperture in one end of said envelope, a cylindrical grid structure surrounding and located coaxially with said aperture and including a plurality of closely spaced wires closing the end of the cylinder nearest said first chamber, anode coaxially disposed of extending into the open end of said cylindrical grid structure from without said first chamber, a cathode located in said first chamber, sealing means extending between portions of said envelope surrounding and in close proximity to said aperture and an intermediate portion of said anode so that a second low pressure gas filled chamber is formed thereby.

25 6. A gaseous switch tube comprising an envelope enclosing a volume of gas under low pressure, a cylindrical grid structure including a plurality of closely spaced wires closing one end of the cylinder disposed in and dividing the envelope into two chambers, one of said chambers being substantially smaller than the other, an anode electrode located in said one chamber and extending into the open end of said cylindrical grid structure and in close proximity thereto, a cathode located in said other chamber.
